Philip Herz

UNITED STATES PATENT OFFICE

PHILIPP HERZ, OF WINDSHEIM, GERMANY

PROCESS AND DEVICE FOR THE MANUFACTURE OF SEAT AIR CUSHIONS

Application filed April 10, 1928. Serial No. 268,984.

My present invention relates to a process and a device for the manufacture of seat-air cushions for sick-beds. In making air cushions it is usual to employ two rubber 5 plates cut in a suitable shape and disposed above each other, which are connected on their edges in forming two longitudinal parallel seams. Such cushions have the disadvantage that they become untight at the seams 10 after a short use requiring thus lengthy and troublesome repairs. Furthermore the invalid is unfavourably influenced through the pressure exerted by the hard edges of the seams.

15 According to my invention the above mentioned disadvantages are obviated, as the improved air cushion is made without any longitudinal seam and consists of a seam- 60 less circular tube.

20 The accompanying drawing shows by way of example the object of my present invention in which Fig. 1 is a plan view of an air cushion, Fig. 2 is a cross section of Fig. 1 partly in longitudinal section.

25 Fig. 3 is a plan view partly in section of the mandrel, for making the air cushion.

Fig. 4 is a sectional view of the connection for the parts of the mandrel.

The air cushion consists of a circular tube 30 A made without any longitudinal seam. At the joint both ends overlap each other and are fixed together in the well known manner. By this connection only a short outer seam, positioned in a radial plane to the circular cushion 35 ions is formed, which is of no disadvantageous influence whatsoever as the seam is formed in a position which the invalid can avoid by placing the cushion in a suitable manner. The two overlapping ends of the 40 circular tube can moreover easily be tightened, all the more as, by pumping up the cushion, the inner tube end is pressed against the outer one, owing to the existing inner pressure.

45 What I claim is:

A seat air cushion for invalids consisting of a circular tube without any longitudinal seams and having a seam positioned in a radial plane to the cushion body.

In testimony whereof I affix my signature. 50
PHILIPP HERZ.
